UNITED STATES PATENT OFFICE.

FRITZ ALBERT NILSSON, OF JÖNKÖPING, SWEDEN, ASSIGNOR TO JOHN GUSTAF SANDWALL, OF JÖNKÖPING, SWEDEN.

TWO-CYLINDER AND MULTICYLINDER INTERNAL-COMBUSTION ENGINE.

1,283,270.

Specification of Letters Patent.

Patented Oct. 29, 1918.

Application filed January 26, 1917. Serial No. 144,638.

To all whom it may concern:

Be it known that I, FRITZ ALBERT NILSSON, a subject of the King of Sweden, residing at Jönköping, in the Kingdom of Sweden, have invented a new and useful Improvement in Two-Cylinder and Multicylinder Internal-Combustion Engines, of which the following is a specification.

In two-cylinder and other multi-cylinder internal combustion engines it has heretofore been customary to use one ignition chamber for each cylinder. For each cylinder the ignition chamber has been a separate part, and arranged in about the same manner as in one-cylinder engines. It is obvious that with such an arrangement each ignition chamber requires similar attention and inspection as the ignition chamber of a single cylinder engine. In other words, it is necessary to provide one heating lamp for each ignition chamber. It is further necessary to regulate very carefully the supply of fuel and air to each cylinder in order that the temperature of the ignition chambers thereof will not become too high or too low. If, as is often the case for instance in a two-cylinder engine, one of the ignition chambers has a tendency to remain comparatively cold, the effect of this cylinder decreases on account of inferior gasification of the fuel, and it may fail to ignite entirely. The other cylinder will then have to do the whole work, which causes the engine to slow down and its efficiency to decrease. Figuratively speaking, it may be said that as regards the temperature there is an unstable equilibrium between the two ignition chambers, in the arrangement hitherto used.

The present invention relates to an arrangement for automatically equalizing the difference caused for any reason, in the temperature of the ignition chambers of two adjacent cylinders. This equalization of the heat is attained, according to the invention, by the ignition chambers, being cast, or in any other manner produced in one piece, or otherwise connected so that there may be a transmission of heat between the same.

One embodiment of the invention is illustrated in the accompanying drawing. Figure 1 shows a section through the cylinders and the ignition chambers of a two-cylinder engine constructed according to the present

invention. Fig. 2 shows a transverse section on the line *a*—*b* in Fig. 1, through the common double ignition chamber. Fig. 3 illustrates an embodiment of the invention in which the two ignition chambers are cast separately, their inner ends being adapted to abut one against the other whereby the desired transmission of heat is attained.

Referring to Fig. 1, 1 and 2 are the two cylinders having combustion chambers 3 and 4. 5 denotes the double ignition chamber cast in one piece. In the instance shown, it is of tubular shape and provided with enlargements 6 and 7 at both ends, and with a partition 8 at the middle. In order to obtain a convenient injection of the fuel the fastening flanges 13 and 14 of the ignition chamber are inclined in opposite directions relatively to the geometrical axes of the cylinders.

The manner of operation is as follows: If for some reason or other, one of the cylinders, for instance the cylinder 1, obtains more powerful ignitions, and thus the portion 6 of the ignition chamber becomes comparatively hot, a portion of this heat will immediately be transmitted to the colder portion 7. In this manner the ignition chamber of the cylinder 2 will never be so cold that the ignition fails. Only one heating lamp is required for each pair of cylinders. The ribs 10 are intended for strengthening the middle portion of the ignition chamber casting. Owing to the fact that the partition 6 is always hot, because the radiation of heat from the same can only take place slowly and further because it receives heat from both combustion chambers, the heating lamp need not burn when the motor is running light. The holes 9 are intended for the circulation of air for cooling the partition 8 in case it should become too hot. In case a still better cooling is desired, annular ribs 15 may be provided on the ignition chamber casting.

As regards the shape of the ignition chamber casting and the arrangement of the ribs many modifications may be conceived. Longitudinal ribs may for instance be provided, with the intention of directing the flame of the heating lamp toward both ends of the ignition chamber.

In four-cylinder, six-cylinder, and other multi-cylinder engines it is preferable to

provide a double ignition chamber for each pair of cylinders. The possibility of providing a common ignition chamber extending along all cylinders is, however, not excluded.

I claim:

1. In a multi-cylinder internal combustion engine, an ignition chamber for each cylinder, said ignition chambers being cast in groups of at least two, a partition in said casting separating said chambers and provided with channels opening on the outside of said casting, said ignition chambers being of substantially tubular shape with their
- 10 narrowest part at the partition and widening toward their outer ends.

narrowest part at the partition and widening toward their outer ends.

2. In a multi-cylinder internal combustion engine, an ignition chamber for each cylinder, said ignition chambers being cast in groups of at least two, a partition in said casting separating said chambers and provided with channels opening on the outside of said casting, said ignition chambers being of substantially tubular shape with their narrowest part at the partition and widening toward their outer ends, and ribs on the outside of said casting near said partition.

FRITZ ALBERT NILSSON.
